UNITED STATES PATENT OFFICE.

CHARLES H. GAIL, OF CINCINNATI, OHIO, ASSIGNOR TO THE SHOTT MANUFACTURING COMPANY, OF CINCINNATI, OHIO, A CORPORATION OF OHIO.

BEDSPRING.

Application filed June 19, 1920. Serial No. 390,074.

To all whom it may concern:

Be it known that I, CHARLES H. GAIL, a citizen of the United States, residing at Cincinnati, in the county of Hamilton and State 5 of Ohio, have invented certain new and useful Improvements in Bed-Springs, of which the following is a specification.

My invention pertains to bed-springs and concerns particularly the end cross-bar construction of the supporting-frame, especially, though not restrictedly, the foot portion of the frame, its leading aim and prime purpose being to provide a bed-spring which will not sag in the middle or even have the 10 appearance or possible deceptive feeling of sagging. To this end, the spring is made slightly arched crosswise, being a trifle higher in the middle or center than at the two sides, and this is accomplished by correspondingly arching or bowing the transverse end-bars of the frame which support the 15 spring structure, the latter in the preferred embodiment of the invention comprising an underlying metallic fabric or interwoven 20 wire structure connected at its opposite ends by helical springs to the frame and supporting a plurality of upright spiral springs. Also, inasmuch as a greater weight is likely 25 to be imposed on the central part of the bed-spring, either one or both of such end bars is also bowed or curved outwardly, whereby 30 to put a slightly greater tension or stress on the helical springs which support the middle portion of the spring than on those connected to the side sections. Thus, either one or 35 both of these bars has a double curvature, each arching or bowing assisting and doing its part in producing the desired results.

Another object of the invention is to so 40 construct the bed-spring that it will properly and adequately support a mattress shaped to conform to a bow-foot bed, and, accordingly, an extension is provided on the bed-spring which carries that part of the mattress projecting beyond the foot end cross-bar of the 45 spring. Such extension may conveniently comprise a supplementary or auxiliary cross-bar shorter than and mounted on the main, curved, arched end-bar of the frame by 50 means of suitable straps or brackets, and such extension-bar has a row of upright spiral springs carried thereby which underlie and support the corresponding extension forming an integral part of the mattress.

55 To enable those skilled in this art to have

a full and complete understanding of the invention both from structural and functional standpoints, I have illustrated a preferred embodiment of the same in the accompanying drawing which should be considered in connection with the following detailed description. In both views of the drawing like reference characters refer to the same parts.

In this drawing:

Figure 1 is a fragmentary plan view of the foot end portion of the improved bed-spring, the upright, spiral mattress-supporting springs and their border-wire being illustrated in a portion only of the figure 60 and omitted from the remainder thereof to more clearly show the underlying structure;

Figure 2 is a vertical cross-section along the inner edge of the main cross-bar of the supporting-frame shown in Figure 1 on 70 line 2—2.

Inasmuch as the two ends of the structure are of substantially the same construction except for the extension feature of the foot-end of the spring, it has been deemed unnecessary to illustrate the head end part of the construction.

By reference to the drawing, it will be seen that the spring-structure comprises a main-frame composed of tubular longitudinal side-rails 10 and 11 provided at their ends with socket-brackets 12, 12, and on these, as by riveting, an upwardly-arched outwardly-bowed cross-bar 13, desirably angle-shaped in cross-section, is mounted with 80 a substantially-horizontal flange at the top and a vertical flange fastened to the brackets. The upward curvature or arching of the bar is clearly shown in Figure 2, and the outward bowing is fully depicted in Figure 1. 85 Both of these curvatures may be comparatively slight but yet sufficient to produce the results hereinafter indicated.

Such pair of head and foot cross-bars, by means of a number of helical springs 14, 15, and 16 arranged singly and in pairs as shown in Figure 1, and wire and clip connections 17, 18, and 19 support longitudinal wire-strands 20, 20 associated with the cross-connecting wires 21, thus providing a yielding-supported wire network or fabric carried by the main-frame and on which the greater portion of the upright mattress-supporting spiral springs are mounted. As is more clearly shown in Figure 1, the helical 100 105 110

springs are either directly connected to the angle cross-bar 13 by means of their hook-ends, or by means of the wire-sections 19 which have similar hook-ends, taking in 5 holes 22 provided in the top flange of the cross-bar and properly spaced apart for the attachment of these elements. The vertically-disposed spiral-springs 23 of the main body of the structure are mounted on the 10 yieldingly-supported fabric or interlaced supporting wires at their smaller ends at the intersections of the lengthwise and laterally-disposed intersecting wires 20 and 21 in any approved and usual manner. The upper or 15 top coils of such springs are connected together by short helical springs 24 fastened thereto in such a manner as to prevent sliding thereon, hence eliminating any possibility of objectionable squeaking or other noise. 20 It will be seen, therefore, that owing to the upward curvature of the end-bars, the whole mattress is given a slightly arched effect transversely, and because of the outward bowing of the end-bars, the helical 25 springs at the center of the construction are under greater strain than those at the sides, this tension gradually decreasing from the center to the sides. Therefore, greater supporting effect is given to the middle or central 30 portion of the structure, and even though greater weight be imposed upon such part of the spring, it will wholly or in large measure overcome or neutralize any tendency to sagging or depression. 35 By means of a suitable number of strap-bars or brackets 25, 25 a supplementary or auxiliary upwardly-arched extension cross-bar 26 is mounted on the main foot cross-bar 13 for the purpose of supporting the 40 extension row of spiral-springs 27 which are directly mounted thereon, apertures 28 being provided in the bar for this purpose. Such row of springs is of less length crosswise the structure than the corresponding rows of 45 the main body of the spring, as is clearly shown in Figure 1, and these springs are connected to one another and to the other springs of the structure by the flexible or spring connectors 24, and all of the springs 50 of the whole structure are provided with a suitably-formed border or marginal wire 29 to which all of the outer springs are con-

nected in any approved manner. It will thus be perceived that the foot portion of the spring has an extension or auxiliary part of 55 somewhat narrower width adapted to underlie and support that portion of the mattress extended beyond the main cross-bar of the spring and adapted to occupy the bowed portion of the foot of the bed, which, of course, is not shown in these drawings. 60

An understanding of this construction, the method of associating the elements together, the principles of operation, and the modes of function will make clear to those 65 skilled in this art the accomplishment of the several purposes and objects of this invention, but it is to be understood that the latter is not limited and restricted to the precise and exact details of structure illustrated and described because these may be modified within comparatively wide limits without departure from the substance and essence of the invention and without the sacrifice of any of its substantial benefits and advantages. Accordingly it is to be understood that the particular embodiment of the invention presented is merely by way of example, the invention being susceptible of various other incorporations in physical form 70 all falling within the breadth and scope of the invention as defined by the appended claim. 75

I claim:

In a bed-spring structure of the character described, the combination of a main-frame having an upwardly-arched outwardly bowed foot-end cross-bar, a main-spring structure including a plurality of upright spiral-springs and underlying longitudinal supporting-elements for said spiral-springs, helical-springs connecting said longitudinal supporting-elements to said cross-bar, an auxiliary extension upwardly-arched outwardly-bowed cross-bar shorter 90 than and mounted on said foot-end cross-bar, and a cross row of upright spiral-springs forming an extension portion of the bed-spring mounted on said auxiliary cross-bar, such row of springs being of less length 95 than the cross rows of springs of the main-body of the bed-spring, substantially as described. 100

CHARLES H. GAIL.
